UNITED STATES PATENT OFFICE.

HERBERT CHAMPION HARRISON, OF EXTON, PENNSYLVANIA.

ELECTRIC SMELTING-FURNACE.

No. 919,165.

Specification of Letters Patent.

Patented April 20, 1908.

Application filed May 4, 1908. Serial No. 430,712.

To all whom it may concern:

Be it known that I, HERBERT CHAMPION HARRISON, a subject of the King of Great Britain, residing at Exton, in the county of Chester and State of Pennsylvania, have invented certain new and useful Improvements in Electric Smelting-Furnaces; and I do hereby declare the following to be a full, clear, and exact description of the invention, such as will enable others skilled in the art to which it appertains to make and use the same.

My invention relates to smelting furnaces of the arc type, and to methods of operating the same, and has for its object the production of a furnace and a method which will be more efficient in action than heretofore; and a furnace that will be easy to repair and the cost of which, for a given output will be a minimum.

To these ends my invention consists in a furnace of the arc type and a method of operating the same, employing polyphase currents for the purpose of smelting the charge, and using reducing agents, whereby the products of reduction are obtained continuously in the form required by tapping the same, all as more fully hereinafter disclosed and particularly pointed out in the claims.

Referring to the accompanying drawings forming a part of this specification:—Figure 1, is a plan view of a furnace employing three packets of electrodes. Fig. 2, a sectional view of the same, showing the electrode packets in side elevation. Fig. 3, a sectional view taken at right angles to the view of Fig. 2, showing one packet of electrodes in end elevation. Fig. 4, a plan view of a smaller furnace employing only single electrodes. Fig. 5, a sectional view of this smaller furnace showing the single electrodes in side elevation, and Fig. 6, a like view taken at right angles to Fig. 5, showing such electrodes in end elevation.

Like numerals refer to like parts in all the views:—

It is well known that electric smelting furnaces are made of various sizes, and that when they become so large that electrodes 50 in one piece cannot take care of the power required, it is necessary to build up the electrodes of a plurality of pieces thereby forming packets, in order to accommodate large units of power. In Figs. 1, 2 and 3 is illustrated a furnace employing such very large units of power, while in Figs. 4, 5 and 6, is

illustrated a furnace capable of employing only the power that can be carried by single electrodes, all as will appear more fully hereinafter.

Referring to Figs. 1, 2 and 3:—1, represents the furnace proper which is rectangular in shape; 3 the molten bath; and 4, an opening through which the products may be continuously tapped. 5, represents an outer metal covering; 6, a metal bottom; and 7, a suitable refractory bottom lining of carbon conducting material. 2, represents any suitable charge. In the case of the manufacture of ferro alloys, such as ferro silicon, this charge may consist of a mixture of silica, iron, or iron ore, and charcoal or coke, in such proportions as the required product of reduction may determine. Such a charge is of a relatively low conductivity when compared with a product of reduction, such as molten ferro silicon which collects at the bottom of the furnace, and this fact is taken advantage of, as will presently appear. The disposition of the electrode packets 9, and 80 their connections, however, is such that the arcs are always maintained between each electrode and the bath, and never between the electrodes themselves. That is to say, the bath is grounded through the refractory bottom lining 7, and metal bottom 6, as shown at 10; and the neutral point 11, of the star connection 12, of the polyphase generator, is likewise grounded; so that the bath itself is always neutral. The holders or 90 other supports 13, for the electrode packets, are likewise joined to the point 11 of the star connection by the lead wires 14, as shown, and the said packets 9, are spaced just far enough apart to cause the molten bath to be 95 always one and not three separate baths, so that only a very small current passes from one electrode to the other through the unreduced charge, which, as above stated, is relatively highly resisting. In such a furnace, if 100 the highest efficiency is to be attained, the parts must be all so proportioned as to cause the electrode packets, which are oblong in cross section, to be symmetrically placed, as shown in Fig. 1. When single electrodes are 105 employed, evidently a narrower furnace is required for the best results. Therefore, in such cases the parts should be disposed, as shown in Figs. 4, 5 and 6, wherein the furnace 15, is still rectangular, but is made narrower than the one illustrated in Fig. 1. In 110 these figures the electrodes 16, are spaced

apart and disposed relatively to the bath as in the previous figures; the leads are likewise disposed, and the bath made neutral in the same way. In both cases it is desirable, in fact practically essential, to provide a lifting and regulating means 17, for the electrodes, as shown. In working such furnaces, the charge 2 may be continuously fed in from the top while the reduced product may be tapped off from the bottom as required; and to start up such a furnace, a charge relatively high in the metallic element should be employed until the molten bath, mentioned above, is formed, when the ordinary charge is substituted.

My invention should be carefully distinguished from those prior polyphase furnaces acting upon the resistance principle, wherein the electrodes must essentially be placed symmetrically in regard to the neutral point, and which itself must be of the nature of an electrode. Such an arrangement practically presupposes a circular furnace which is more expensive to build and complicates the regulation of the electrodes. In my furnace on the other hand it is not essential to arrange the electrodes symmetrically with the neutral point, which is in reality the molten bath itself; it is only necessary to balance the phases by a careful regulation of the arcs maintained between each electrode and this neutral bath. My invention should likewise be carefully distinguished from those polyphase furnaces, such as are disclosed in German Patent No. 150,262, June 12, 1903, to Seemen. In this furnace the electrodes are inclined, thereby necessitating that they be moved greater distances, than would be the case if they were vertically disposed, whenever the length of the arcs is adjusted. Furthermore, the length and weight of the electrodes, when large furnaces are employed, must be such that inclined electrodes would be liable to break with their own weight; especially when adjusted by cranes or power as they must be in practice. Again, such electrodes in large furnaces would tend to burn unevenly, owing to the varying distances between their surfaces and the molten bath. Also owing to their inclined and circular disposition, it would be exceedingly difficult to keep the phases balanced. In addition to this, it would be impossible to combine the electrolysis feature of this German patent to my furnace, on account of the fact that my electrodes being arranged in a row of packets or row of single electrodes, the middle electrode will necessarily occupy the place which the fourth or electrolyzing electrode in this German patent must occupy, which is the central position with regard to the molten bath. In fact the furnace of this German patent is necessarily a small one, and it would not be possible to employ large units of power on this principle.

I avoid all the foregoing objections in prior polyphase furnaces, by, among other things, making my furnaces rectangular and so proportioned as to be able to place my rectangular electrodes all in a row. At the same time, I secure the advantages of being able to save current over ordinary direct current, and single phase furnaces employing a plurality of electrodes in line, because all of my arcs are efficient; owing to the fact that I obtain a maximum periphery to each arc for a given amount of power. Furthermore, I save over a single phase furnace of similar capacity, half the weight of conductors necessary for a given amount of power. This is because both the neutral point of the star connection on the generator, and the neutral bath in the furnace are grounded, thus doing away with a fourth return wire which would have to be large enough to carry the whole of the current. Moreover, commercial electric power is now generally delivered in the form of polyphase currents, and instead of being compelled to use three separate single phase furnaces, which necessarily entails greater maintenance charges and greater labor costs, I am enabled to use this power directly in my furnace without converting it into any other form, thereby effecting a great saving over the employment of three separate furnaces, and also saving the expense of conversion, and the losses incident thereto when a single phase current is employed. Another important advantage my furnace possesses over the direct, or single phase type, is the ability to put very much more power into a furnace of a given size, and thereby securing all the benefits flowing from such fact.

The above differences, while of little or no consequence in those furnaces using only a few horse power, are nevertheless of the highest importance in furnaces using thousands of horse power. For in such larger furnaces, every objection inherent in the small furnace becomes enormously magnified; and unless remedied, efficient results will be derated and large sums of money wasted.

Of course I do not wish to be understood as limiting myself to the exact details and arrangement above disclosed, since it is evident that both may be varied by those skilled in the art, without departing from the spirit of my invention.

What I claim is:

1. The method of utilizing polyphase currents to effect reductions in electric furnaces of the arc type, which consists in vertically disposing arc electrodes in the furnace; in connecting each electrode to one of the branches of the star connection of a polyphase generator; in so spacing the electrodes that a single bath is formed and an arc between each electrode and said bath is also formed; and in placing resisting charge ma-

terial between said electrodes to prevent any substantial leakage of current from electrode to electrode, substantially as described.

2. The method of utilizing polyphase currents to effect reductions in electric furnaces of the arc type, which consists in first charging said furnaces with a charge relatively high in metal until a molten bath is formed, then charging said furnaces with a charge of a lower conductivity than said first charge; vertically disposing arc electrodes in the furnace; connecting each electrode to one of the branches of the star connection of a polyphase generator; and placing resisting charge material between said electrodes to prevent any substantial leakage of current from electrode to electrode, substantially as described.

3. An electric furnace of the arc type rectangular in shape, adapted to use polyphase currents, provided with a plurality of vertical arc electrodes, placed in a row, and having a metal bottom electrically connected with the molten bath of said furnace; in combination with a polyphase generator provided with a star connection and suitable electric

connections between said star connection and the ground, between said metal plate and the ground, and between said star connection and each of said electrodes, substantially as described. 30

4. In a polyphase electric furnace of the arc type having a rectangular shape, the combination of three arc electrode packets, each packet of an oblong rectangular shape, vertically disposed in a row; means to adjust said packets up and down; a metal bottom for said furnace; a ground connection for said bottom; a refractory conducting material above said bottom, a polyphase generator provided with a star connection; and connections between the same and said packets, and a connection between said star and said ground, substantially as described. 35

45 In testimony whereof I affix my signature, in presence of two witnesses.
